UNITED STATES PATENT OFFICE

FRED I. RAYMOND, OF RIVER FOREST, ILLINOIS

SODA FOUNTAIN

Application filed March 20, 1929. Serial No. 348,483.

This invention relates to improvements in soda fountains, or similar refrigerating apparatus, and more particularly to new and improved means for automatically maintaining the soda, drinking water, or other liquid that is intermittently drawn through the fountain at approximately the desired temperature. In the modern soda fountain, it is desirable that several different temperatures, 10 all below the prevailing atmospheric temperature, be maintained in different portions of the fountain, for example, in the compartment or compartments for storing ice cream, the compartment or tank for cooling soda 15 and the drinking water, the compartment where the syrups are stored, and the general storage compartment for bottled goods and similar articles.

The present invention relates particularly 20 to means for maintaining the soda and drinking water at substantially a constant and proper temperature. This is particularly difficult, due to the fact that the cooled supply of these liquids is being intermittently 25 drawn upon in varying amounts.

According to the present invention, a main brine tank is provided with suitable cooling means whereby the brine in this tank is maintained at a desired low temperature. 30 This temperature will be quite low, usually that required for storing the ice cream, and consequently lower than the temperature desirable for the soda or drinking water. The coolers or coils through which the soda or 35 drinking water, or both, pass, are positioned in an auxiliary tank containing refrigerated brine. The brine in this auxiliary tank will be cool, but will be at a higher temperature than the brine in the main tank, and means 40 are provided for intermittently circulating brine from the main tank into the auxiliary tank, in order to maintain the brine in this auxiliary tank at the desired temperature. As this brine rises in temperature, additional 45 cold brine will be forced in from the brine in the main tank. The cooler is connected in circuit with conduits leading from the source of supply so that the liquid will flow into the cooler and from the cooler to the 50 faucet from which the liquid is intermittent-

ly drawn off. When cooled liquid is withdrawn from the cooler, warmer liquid will flow in from the source of supply to take its place, and it is then desirable that the temperature of the brine in the auxiliary tank be lowered so as to quickly lower the temperature of this new supply of liquid in the cooler. According to the present invention, 55 an automatic valve is located in the conduit leading from the cooler to the faucet, this valve being normally closed, but automatically opening when there is a flow of liquid through the valve. This automatic valve controls means for forcing, or permitting, 60 liquid to flow from the main brine tank into the auxiliary tank. Consequently, whenever liquid is withdrawn from the cooler, a new supply of colder brine will flow into the auxiliary tank to withdraw the surplus heat 65 from the liquid that has been drawn into the cooler to replace the supply just drawn off. 70 The general object of this invention is to provide a new and improved refrigerating system for soda fountains or similar apparatus, substantially as referred to hereinabove and as described more in detail in the specifications which follow. 75

Another object is to provide improved means for intermittently applying a cooling 80 medium to the liquid in a conduit, whenever this liquid is intermittently caused to flow through this conduit, or partially withdrawn therefrom.

Another object is to provide means for renewing the cooling medium within a tank, in 85 which a cooler is positioned, whenever the liquid within this cooler is withdrawn and replaced by liquid at a higher temperature.

Other objects and advantages of this invention will be more apparent from the following detailed description of certain approved forms of apparatus operating according to the principles of this invention. 90

In the accompanying drawings:

Fig. 1 is a view, partially in elevation and partially in vertical section, of a portion of a soda fountain showing diagrammatically the improved cooling system. 95

Fig. 2 is a detail view showing the auto- 100

matic valve in vertical section, and showing the control switch in elevation.

Fig. 3 is a view similar to Fig. 1, showing a modification.

5 Fig. 4 is a vertical section through the automatic cut-off valve.

Referring first to Figs. 1 and 2, the soda fountain comprises a larger lower portion 1, housing a plurality of separate compartments 10 for storing and cooling different materials, this portion having a top 2 in the form of a horizontal shelf provided with openings for gaining access to certain of the compartments, and a front upwardly projecting portion 3 15 providing a compartment for the syrup dispensers 4 and from which project the draft arms 5 and 6 for dispensing soda and ice water respectively. Certain of the walls of the soda fountain may be made double, as indicated at 7 and 8, the space between being filled with insulating material 9. It is to be understood that the refrigerating apparatus and the fluid and electric circuits are illustrated diagrammatically, and not in the size, 20 relative proportions and exact locations that would be found in an actual construction.

A main compartment or tank 10 is adapted to be filled with brine, in which is positioned a receptacle or freezer 11 for holding ice cream. Access to this receptacle is through an opening in the top 2 of the fountain. It is desirable that the temperature in this tank or compartment 10 be quite low, for example, from 0 degrees to 5 degrees Fahrenheit. 25 Within the brine in this compartment 10 is positioned some suitable form of refrigerating element, such as the "boiler" shown at 12. This boiler is in the form of a coil or assemblage of grouped tubular members in which a compressed and liquefied material admitted through the inlet pipe 13 expands and vaporizes, the gas passing out through pipe 14. The process of expansion of this refrigerating medium serves to absorb heat from the 30 brine in tank 10 in a well known manner. A temperature regulating control valve 15 in supply pipe 13 serves to limit the flow of the refrigerating medium to the boiler and thus regulate the temperature that is maintained 35 in the brine tank 10. It is to be understood that the refrigerating element just described is shown by way of example and that any other form of refrigerating means might be used for maintaining the brine in tank 10 at 40 the proper temperature. It is to be understood that the term "boiler" is used in the following description and in the claims as intended to designate any equivalent form of refrigerating element for keeping the brine 45 or other fluid in the tank at the proper low temperature.

A second compartment or brine tank 16 may be positioned adjacent the main tank 10 and adapted to house freezers for bulk 50 ice cream, or other materials. The tempera-

ture in this compartment may be somewhat higher than in compartment 10, for example, from 10 degrees to 12 degrees Fahrenheit, and suitable means are provided for circulating a portion of the brine from tank 10 70 through tank 16 to maintain this desired temperature. This system forms no part of the present invention, but is disclosed more in details and claimed in my copending application Serial No. 347,947 filed March 18, 1929. 75

An auxiliary brine tank 17 for cooling the soda, or drinking water, or both, is positioned at one side of or in one corner of the large compartment 18 which is used for general storage purposes. The soda and plain water 80 that are refrigerated by the brine tank 17 should be kept at a temperature of from 33 degrees to 40 degrees Fahrenheit, whereas a temperature of from 40 to 45 degrees Fahrenheit is proper in the refrigerating compartment 18. This compartment 18 is cooled by conduction from the brine tank 17 positioned therein. Within the brine tank 17 is positioned a cooler 19 through which the soda is circulated in the example here shown. It is 85 to be understood that a similar but separate cooler may be used for cooling the drinking water, this cooler being positioned within the same auxiliary tank 17, or within a similar auxiliary tank. Preferably the cooler 19 will 90 be designed to hold about one-half the volume of auxiliary tank 17, so that the volume of liquid in cooler 19 will be approximately the same as the volume of brine surrounding the cooler in tank 17. The cooler 19 may be 95 of any approved tubular or cellular construction so as to provide a large external heat conducting surface.

The soda or other liquid flows in from the source of supply through pipe 20 at one end 105 of the cooler and passes out through pipe 21, preferably connected with the opposite end of the cooler. The pipe or conduit 21 leads into the automatic valve 22 (hereinafter described), and conduit 23 leads from the valve 110 22 to the draft arm 5. Whenever the faucet 24 on draft arm 5 is opened, soda will flow out from cooler 19 through conduits 21, 22 and 23, and new liquid at a higher temperature will flow into the cooler from the source of 115 supply through pipe 20. When faucet 24 is closed, this flow will cease.

The automatic valve 22 is disclosed more in detail in Fig. 2. The outlet conduit 23 is tapped into the top of the hollow valve casing 120 25. A hollow cylinder 26 is screwed or otherwise secured in one side of casing 25, and the inlet pipe 21 is tapped into the otherwise closed outer end of this cylinder. The open inner end of this cylinder is provided with a 125 slightly enlarged cylindrical bore 27, in which is received a piston or plunger 28. This piston is adapted to seat against a shoulder 29 at the inner end of bore 27 to limit its movement in one direction. The piston 28 is con- 130

nected with one end of a piston rod or stem 30 which projects out through a guide passage 31 in the opposite side of valve casing 25. A spring 32 surrounding the piston rod 30 and confined between the piston and the inner wall of the valve casing serves to normally urge the piston 28 into position within the cylinder 26 and against the stop shoulder 29.

When faucet 24 is opened and liquid is drawn off through conduit 23 from casing 25, liquid will tend to flow in through inlet pipe 21 to replace the liquid thus drawn through the valve, and this inflowing liquid will force piston 28 from the cylindrical passage 27 against the resistance of spring 32, thus moving piston rod 30 toward the right, Fig. 2. When this flow ceases, due to the closing of faucet 24, the spring 32 will return the piston 28 into the cylinder.

The tube 33 of a mercury switch is mounted in a frame 34 pivotally mounted for oscillation about the axis 35. The lower arm 36 of frame 34 is connected by link 37 with the outer end of piston rod 30. As the piston rod 30 is moved back and forth in response to the movements of piston 28, the frame 34 will be tipped from one side to the other of the vertical plane through axis 35, and the tube 33 will be inclined in one direction or the other so as to cause the mercury globule 38 therein to run from one end of the tube to the other. In one end of tube 33 is mounted a pair of normally separated contacts 39 and 40, from which lead respectively the electric conduits 41 and 42. When the switch is in the position shown in Fig. 2, the circuit will be broken. When the switch is tilted in the opposite direction, a circuit will be completed through conduits 41 and 42 since the contact members 39 and 40 will be bridged by the mercury globule 38. It will now be apparent that when the faucet 24 is closed and there is no flow of liquid through valve 22, the piston 28 will be forced to the left by spring 32 and the switch will be moved to open position. When faucet 24 is opened and there is a flow of liquid to the valve, the piston 28 will be moved out of the cylinder 26 and the switch will be moved to closed position so as to complete the circuit through conduits 41 and 42.

An inlet brine conduit 43 leads from the lower portion of main tank 10 into one end of auxiliary tank 17, and a pump 44 of suitable form is positioned in this conduit 43. When pump 44 is not in operation, no flow of brine will be permitted through the conduit 43. When pump 44 is operated, brine will be withdrawn from tank 10 and forced into the auxiliary tank 17. A motor 45 for operating pump 44 is connected in the actuating circuits 41 and 42 controlled by switch 33. A return conduit 46 leads from the other end of auxiliary tank 17 back into the lower portion of main brine tank 10, preferably with an

upward extension 46' to discharge the returned brine into the upper portion of the tank. When pump 44 is operated, cold brine will be withdrawn from the lower portion of tank 10 and forced into the auxiliary tank 17 and the warmer brine in tank 17 will be forced out through conduit 46 and returned into the upper portion of main brine tank 10. This not only serves to lower the temperature of the brine in auxiliary tank 17, but also creates a circulation of the brine in main tank 10, thus keeping the brine in this tank in motion so as to prevent the salt from settling out to the bottom of tank 10.

It will now be apparent that whenever liquid is withdrawn from the supply in cooler 19 and replaced by warmer liquid through inlet pipe 20, a portion of the brine in auxiliary tank 17 will be forced out and replaced by colder brine from the tank 10. If the relative volumes of the liquid in cooler 19 and the brine in tank 17 are properly proportioned, the heat absorbed from the liquid in cooler 19 by the colder brine in the auxiliary tank 17 will be just sufficient to lower the temperature of this liquid in the cooler to the desired point. Whenever the temperature of the liquid supply in cooler 19 is raised by withdrawing liquid therefrom and replacing it by warmer liquid from the outside supply, the temperature of the brine in tank 17 will be correspondingly lowered by the admission of colder brine from the main tank 10. The heat subsequently transmitted from the liquid in cooler 19 to the brine in tank 17 will result in the temperature of this new liquid supply being lowered to the desired point. It will be apparent that the operation is entirely automatic, and depends solely on the operation of the faucet 24, by means of which liquid is withdrawn through the draft arm 5.

As already stated, this apparatus, or an exactly similar apparatus, could be used in connection with the drinking water supply which is withdrawn through draft arm 6. Separator coolers for both the soda and the drinking water might be positioned in the same tank 17 and the brine flow controlled by the flow of either one or both of these liquids, in the manner already described.

In the modification shown in Figs. 3 and 4, parts not otherwise specifically referred to may be the same as those described in the first form of the invention. In this modified form of the invention, the auxiliary tank 47 is connected at its lower end by a conduit 48 and at its upper end by conduit 49 with the lower and upper portions, respectively, of the main brine tank 10 so as to form a thermo-siphon loop whereby the warmer brine in tank 47 will be automatically replaced by colder brine from tank 10. A cut-off valve 50 in the inlet conduit 48 will, when closed,

prevent the flow of cold brine from tank 10 into auxiliary tank 47.

Referring now to Fig. 4, it will be seen that the cut-off valve 50 comprises a vertically 5 slidable gate valve 51 which when lowered will prevent the flow of brine through conduit 48. When gate valve 51 is raised to the position shown in Fig. 4, brine will be permitted to flow through the conduit 48. The 10 automatic valve shown at 52 operates in substantially the same manner as the automatic valve 22 previously described. The inlet pipe 53 for the soda or other liquid leads from the source of supply into the lower end of 15 valve casing 54. A piston or plunger 56 is normally forced down into the cylindrical bore 55 by the compression spring 57. A piston rod or stem 58 connects piston 56 with the gate valve 51 so that when piston 56 is forced 20 to its lower position, the gate valve will be automatically closed. A flow of liquid into the valve casing through inlet pipe 53 serves to elevate the piston 56 out of the cylinder 55 and thereby open the gate valve 51. The 25 conduit 59 tapped into the upper end of the valve casing leads into the upper portion of cooler 60 within the auxiliary tank 47. An outlet conduit 61 leads from the lower end of cooler 60 to the draft arm 5 and faucet 24.

30 When faucet 24 is opened, the coolest liquid from the lower portion of cooler 60 will be withdrawn through conduit 61. Warmer liquid from the source of supply will flow in through inlet conduits 53 and 59 to the upper 35 portion of cooler 60, thus resulting in the opening of automatic valve 52 and the consequent opening of gate valve 51 so that a flow of colder brine from main tank 10 will be permitted into the auxiliary tank 47. Otherwise the general operation of this modification 40 is the same as already described in connection with the first form of the invention.

In both of the automatic valves 22 and 52, a small bleeding passage 62 may be provided 45 through the respective pistons 28 and 56. This will permit a relatively small flow of liquid through the conduit without operating the valve so as to compensate for any possible leakage at the faucet 24 or other draft mechanism.

I claim:

1. In a refrigerating apparatus, a conduit for liquid, a cooler forming a part of said conduit, means for controlling the flow of liquid through the conduit, a valve in the conduit actuated to open position by the flow of liquid therethrough, and means controlled by the valve for directing a cooling medium against the cooler when the valve is open.

60 2. In a refrigerating apparatus, a conduit for liquid, a cooler forming a part of said conduit, means for controlling the flow of liquid through the conduit, a valve in the conduit actuated to open position by the flow of liquid therethrough, a tank in which the

cooler is positioned, and means controlled by the valve for permitting the flow of a cooling medium through the tank when the valve is open.

3. In a refrigerating apparatus, a conduit 70 for liquid, a cooler forming a part of said conduit, means for controlling the flow of liquid through the conduit, a valve in the conduit actuated to open position by the flow of liquid therethrough, a tank in which the cooler is positioned, and means controlled by the valve for forcing a cooling medium through the conduit when the valve is open.

4. In a refrigerating apparatus, a conduit 80 for liquid, a cooler forming a part of said conduit, means for controlling the flow of liquid through the conduit, a valve in the conduit actuated to open position by the flow of liquid therethrough, a tank in which the cooler is positioned, a pump for forcing a cooling medium through the tank, a motor 85 for actuating the pump, a switch in the motor circuit, and connections for closing the switch when the valve is moved to open position.

90 5. In a refrigerating apparatus, a main brine tank, means for cooling said brine, an auxiliary brine tank, an inlet pipe for conducting brine from the main tank to the auxiliary tank, an outlet pipe for returning brine from the auxiliary tank to the main tank, a pump in one of the pipes, a motor for operating the pump, a switch in the motor circuit, a cooler in the auxiliary tank, a liquid supply conduit leading into and out of the cooler, 95 a valve in the supply conduit, said valve being normally closed but opening automatically when there is a flow of liquid through the line, and operating connections between the valve and the switch whereby the motor circuit will be closed when liquid flows through the supply conduit.

100 6. In a refrigerating apparatus, a main brine tank, means for cooling said brine, an auxiliary brine tank, an inlet pipe for conducting brine from the main tank to the auxiliary tank, an outlet pipe for returning brine from the auxiliary tank to the main tank, a pump in one of the pipes, a motor for operating the pump, a switch in the motor circuit, a cooler in the auxiliary tank, a liquid supply conduit leading into and out of the cooler, 105 a valve in the supply conduit, said valve comprising a valve casing having a cylinder and a piston therein, a spring for normally holding the piston within the cylinder, the flow of liquid through the valve serving to force the piston out of the cylinder against the action of the spring, a piston rod projecting from the valve casing, and operating connections 110 between the piston-rod and switch.

115 7. In a refrigerating apparatus, a main brine tank, means for cooling said brine, an auxiliary brine tank, inlet and outlet pipes connecting the tanks for permitting a ther- 120

mosiphon flow of brine therebetween, a cut-off valve in one of the pipes, a cooler in the auxiliary tank, a liquid supply conduit leading into and out of the cooler, a valve in the supply conduit, said valve being normally closed but opening automatically when there is a flow of liquid through the supply conduit and connections between the two valves whereby they are caused to open and close in unison.

8. In a refrigerating apparatus, a main brine tank, means for cooling said brine, an auxiliary brine tank, inlet and outlet pipes connecting the tanks for permitting a thermosiphon flow of brine therebetween, a cut-off valve in one of the pipes, a cooler in the auxiliary tank, a liquid supply conduit leading into and out of the cooler, a valve in the supply conduit, said valve comprising a valve casing having a cylinder and a piston therein, a spring normally holding the piston within the cylinder, the flow of liquid through the valve serving to force the piston out of the cylinder, and a piston rod projecting from the piston through the valve casing and operatively connected with the cut-off valve whereby the valves are caused to open and close in unison.

9. In a refrigerating apparatus, a main brine tank, means for cooling the brine therein, an auxiliary brine tank, a cooler in this tank, a liquid supply conduit comprising pipes leading into and out of the cooler, a valve in the supply conduit which is automatically opened by the flow of liquid through the conduit, pipe connections permitting a flow of brine through the auxiliary tank from and back to the main tank, and flow controlling means in said pipe which are actuated by movements of the valve.

10. In a refrigerating apparatus, a main brine tank, means for cooling the brine therein, an auxiliary brine tank, a cooler in this tank, a liquid supply conduit comprising pipes leading into and out of the cooler, a valve in the supply conduit which is automatically opened by the flow of liquid through the conduit, pipe connections permitting a flow of brine through the auxiliary tank from and back to the main tank, and means for cutting off the flow of brine through the auxiliary tank when the valve is closed.

11. In a refrigerating apparatus, a main brine tank, means for cooling the brine therein, an auxiliary brine tank, a cooler in this tank, a liquid supply conduit comprising pipes leading into and out of the cooler, a valve in the supply conduit which is automatically opened by the flow of liquid through the conduit, pipe connections permitting a flow of brine through the auxiliary tank from and back to the main tank, and means for causing a flow of brine through the auxiliary tank when the valve is opened.

12. In a refrigerating apparatus, a main brine tank, means for cooling the brine therein, an auxiliary brine tank, a cooler in this tank, a liquid supply conduit comprising pipes leading into and out of the cooler, a valve casing in the supply conduit comprising a casing having a chamber and a cylinder opening into the chamber, a piston in the cylinder, a spring normally holding the piston within the cylinder, a piston rod projecting from the piston through the casing, the flow of liquid through the casing serving to move the piston out of the cylinder into the chamber against the action of the spring, pipe connections permitting a flow of brine through the auxiliary tank from and back to the main tank, and flow controlling means in said pipe connections which are actuated by the movements of the piston.

13. In a refrigerating apparatus, a main brine tank, means for cooling the brine therein, an auxiliary brine tank, a cooler in this tank, a liquid supply conduit comprising pipes leading into and out of the cooler, a valve casing in the supply conduit comprising a casing having a chamber and a cylinder opening into the chamber, a piston in the cylinder, a spring normally holding the piston within the cylinder, a piston rod projecting from the piston through the casing, the flow of liquid through the casing serving to move the piston out of the cylinder into the chamber against the action of the spring, pipe connections permitting a flow of brine through the auxiliary tank from and back to the main tank, electrically actuated flow controlling means in the pipe connections, and a switch actuated by the piston rod and controlling the electrically actuated means.

14. In a refrigerating apparatus, a main brine tank, means for cooling the brine therein, an auxiliary brine tank, a cooler in this tank, a liquid supply conduit comprising pipes leading into and out of the cooler, a valve casing in the supply conduit comprising a casing having a chamber and a cylinder opening into the chamber, a piston in the cylinder, a spring normally holding the piston within the cylinder, a piston rod projecting from the piston through the casing, the flow of liquid through the casing serving to move the piston out of the cylinder into the chamber against the action of the spring, pipe connections permitting a flow of brine through the auxiliary tank from and back to the main tank, a pump in the pipe connections, a motor for operating the pump, an actuating circuit for the motor, a switch in this circuit, and connections between the piston rod and switch for closing the switch when the valve is open and vice versa.

15. In a refrigerating apparatus, the combination of a main brine tank, an auxiliary brine tank, a cooler in said auxiliary tank, and means responsive to the flow of liquid

through said cooler for controlling the flow of brine from said main tank into said auxiliary tank.

16. In a refrigerating apparatus, the combination of a main brine tank, an auxiliary brine tank, a cooler in said auxiliary tank, means comprising a valve controlled by the flow of liquid through said cooler for controlling the flow of brine from said main tank into said auxiliary tank.

17. In a refrigerating apparatus, a main brine tank, means for cooling the brine therein, an auxiliary brine tank, a cooler in said auxiliary tank, a liquid supply conduit comprising pipes leading into and out of said cooler, means controlled by the flow of liquid through said conduit, pipe connections permitting flow of brine through the auxiliary tank from and back to the main tank, and flow controlling means in said pipe actuated by movements of said first-named means.

18. In a refrigerating apparatus, a conduit for liquid, means controlling the flow of liquid through the conduit, a valve in the conduit actuated to open position by the flow of liquid therethrough, and means controlled by said valve for directing a cooling medium into heat exchanging relationship to said conduit for cooling said conduit when said valve is open.

19. In a refrigerating apparatus, the combination of a main brine tank, an auxiliary brine tank, a cooler in said auxiliary tank, connections between said tanks producing thermosiphon flow of brine therebetween, and means responsive to the flow of liquid through said cooler for controlling the flow of brine from said main tank into said auxiliary tank through said thermosiphon connection therebetween.
